UNITED STATES PATENT OFFICE.

HARRY A. LOSER, OF BALTIMORE, MARYLAND.

ADJUSTABLE AND VARIABLE CENTERING FOR CONCRETE ARCHES, &c.

1,112,542.

Specification of Letters Patent.

Patented Oct. 6, 1914.

Application filed February 18, 1913. Serial No. 749,126.

To all whom it may concern:

Be it known that I, HARRY A. LOSER, a citizen of the United States, residing at Baltimore, in the State of Maryland, have 5 invented certain new and useful Improvements in Adjustable and Variable Centering for Concrete Arches, &c., of which the following is a specification.

My invention relates to adjustable and 10 variable centering for reinforced concrete arches, bridges, culverts, tunnels and sewers, and in all places where it is necessary to use a curved supporting frame during construction work.

15 The objects of my invention are first, to provide a construction of centering which is strong and compact in form and cheaply manufactured, and at the same time be quickly assembled, adjusted in position, and 20 removed or knocked down in the shortest time, after the concrete arch has set, and transported to be again set up with the least cost; second, to provide a series of independent and adjustable sections which coöperate 25 with an adjustable center section, whereby an arch of any radius not necessarily a multiple of the center section, and any depth, may be quickly and cheaply constructed; third, further objects and advantages of 30 construction which will readily appear from the detailed description of the apparatus and mode of operating the same.

The invention consists of structural characteristics and relative arrangements of the 35 several parts as will be hereinafter more fully set forth and particularly pointed out in the appended claims.

Reference is to be had to the accompanying drawings wherein similar reference 40 characters indicate the same parts in the several figures, in which—

Figure 1 is a side elevation of the invention as it appears when assembled; Fig. 2 is a side view, partly in section, and on an 45 enlarged scale, of two of the adjustable sections, forming the centering; Fig. 3 is an end view on an enlarged scale of an adjustable section; Fig. 4 is an enlarged side view, half in section and half in elevation, of the 50 adjustable center section; and Fig. 5 is a section taken on line V—V, of Fig. 4.

Referring to the drawings 1, 1, are pin seats, resting upon screws or jacks 2, 2, capable of vertical adjustment and bearing 55 against blocks 3, 3, capable of adjustment on upright blocks 4, 4, and held in a fast and

rigid position by means of horizontal wedges 5, 5, said jacks 2, 2, and upright blocks 4, 4, abutting against suitable piers or abutments 6, of concrete, placed in proper 60 position before the centering is put in place and the arch is poured, and forms no part of the present invention.

The intermediate sections 7, 7, are composed of triangular trusses made preferably 65 of base members composed of channel irons 8, 8, and side members 9, 9, composed of angle irons, rigidly connected at one end to said base members by plates 9', 9' riveted to said base and side members and at their 70 other or apex end of the truss, to plates 10, 10. Said angle irons 9, 9, are connected and braced together by cross pieces 11, 11, which securely hold the pieces forming the triangular trusses together in one rigid whole. 75 The base members 8, 8, have secured to their ends plates 12, each of which is provided with a round opening 13 to receive a pin 14, and hingedly connect the said intermediate sections 7, 7, at the ends of their bases. 80

The plates 10 near the inner ends of angle irons 9, 9, are provided with openings 15 to receive pins 16 which pass through the eyes of right and left screw threaded rods 17, the ends of which are engaged by turn- 85 buckles 18, as shown in Fig. 2. At the extreme outer end of each of the plates 10 is provided a hole 19 through which is passed a suitable rod 20 connecting the lower ends of two or more of the sections 7, 7, to insure 90 lateral rigidity, and said rod is kept from sliding through said holes 19 by a circular clamp 21 interposed between the ends of the plates 10 and encircling and firmly gripping the rod 20. The adjustable center section 95 shown in Figs. 4 and 5 is composed of a strut member 23 and two adjustable members 24, 24, adapted to slide over the ends of the said strut member. The strut member is preferably of a hollow or box form and is 100 composed of two pieces 25, 25, U-shaped in cross section, and connected together by side pieces 26, 26, which side pieces are provided with a series of holes to receive bolts 27, 27, as shown. The adjustable members 24, 24, 105 are likewise made of hollow or box form and adapted to fit and easily slide over the ends of the strut member 23, and consist of two U-shaped pieces 28, 28, and side pieces 29, 29, riveted together as shown. The side pieces 29, 29, have slots 30, 30, corresponding to the bolt holes in the strut member 23

and at the lower ends are holes 31, for the purpose of receiving a pin 16 to engage the eye of a threaded rod 17 similar to that described with respect to the intermediate sections 7, 7. Each of said adjustable members 24 are provided at their upper and outer ends with a plate 24' with a hole 25' to receive a pin 14, similar to and as described with reference to the intermediate sections 10 7, 7.

- The end sections 32, 32, see Fig. 1, are composed of a riveted structural truss frame as shown, and provided with pins 33 for connecting the same to the pin seats 1, 1. 15 The arrangements for attachment to the adjacent intermediate section may be of any other form and construction, if so desired, and forms no essential part of the present invention.
- 20 34 is a flooring over the top of the centering which in turn carries any suitable covering 35 to sustain the mixed concrete 36 and form a finished surface to the curved outer side of the concrete arch, when the centering, flooring and covering are removed.

From the foregoing disclosure it will be seen that in an arch whose length is not an exact multiple of the intermediate section 7, 30 the center section can be adjusted so that the members 24, 24 firmly abut against the adjacent intermediate sections 7, 7, as shown in Fig. 1 when the bolts 27, 27, are screwed up, thereby securely holding together said center section to receive the weight of the load when the concrete is filled in to form the arch. The curvature of the arch can also be easily changed and the adjustment of any particular intermediate section 7 can 40 be readily effected, by simply turning one, several, or all of the turnbuckles 18 to properly and uniformly distribute the load on the centering. After the concrete has hardened and the arch is self supporting, the 45 centering can be readily removed in sections and easily transported to be again set up.

What I claim is:—

1. An intermediate section for an adjustable or variable centering to form concrete 50 arches comprising a triangular truss having a base member, and side members having one of their ends connected to opposite ends of the base and their other ends connected to each other to form the apex of the truss, 55 means at the ends of the base member for pivotally connecting the same to an adjoining intermediate section, a pin rigidly supported in said section at the apex of the

truss, and two separate and independent rods pivotally connected at one of their ends 60 to said pin and free at the other end, and means adjustably connecting the free ends of each two adjacent rods.

2. An intermediate section for an adjustable or variable centering to form concrete 65 arches comprising a triangular truss having a base member having pin openings at its ends, and side members having one of their ends connected to the opposite ends of the base and their 70 other ends connected to each other to form the apex of the truss, removable pins inserted in the openings at the ends of the base member for pivotally connecting one section to an adjoining section, a pin rigidly 75 supported in said section at the apex of the truss, two separate and independent rods pivotally connected at one end to said pin in said apex of the truss and threaded at the other end, and means adjustably connecting the threaded ends of each two adjacent rods.

3. An adjustable center section for an adjustable or variable centering to form concrete 85 arches comprising a central strut member, an adjustable side piece adapted to be connected to each of the ends of the strut member, and means for rigidly locking said strut member and side pieces together after having been properly adjusted with respect 90 to each other, and means at the bottom of each of said side pieces for adjustably connecting a truss of the centering to each of said side pieces.

4. An adjustable center section for an adjustable and variable centering to form concrete 95 arches comprising a central strut member, an adjustable side piece adapted to slide over each of the ends of the strut member, and fastening bolts passing through the 100 strut member and side pieces for rigidly locking said strut member and side pieces together after having been properly adjusted with respect to each other, means at the top of each of said side pieces 105 for pivotally connecting a truss of the centering to each of said side pieces, and means at the bottom of each of said pieces for adjustably connecting a truss of the centering to each of said side pieces.

In testimony whereof I affix my signature in presence of two witnesses.

HARRY A. LOSER.
